UNITED STATES PATENT OFFICE.

SYLVESTER R. CHANDLER, OF BALTIMORE, MARYLAND, ASSIGNOR OF ONE-FOURTH TO ADELBERT W. MEARS, OF SAME PLACE.

DESIGN FOR A BOTTLE.

SPECIFICATION forming part of Design No. 27,885, dated November 23, 1897.

Application filed July 26, 1897. Serial No. 646,043. Term of patent 14 years.

To all whom it may concern:

Be it known that I, SYLVESTER R. CHANDLER, a citizen of the United States, residing at Baltimore, in the State of Maryland, have 5 invented and produced a new and original Design for Bottles, of which the following is a specification.

My present invention pertains to a new and original design for bottles, as will be herein- 10 after described, reference being had to the annexed drawing, wherein the bottle is shown in perspective.

The bottle comprises the base A, rounded off at the top and having extending there- 15 from the upright cylindrical section B. A laterally-extending lip C is formed around the section B, and a spherical section D is formed upon and extends from the inner edge of the lip, the walls of said spherical section

being somewhat thin at the point of connec- 20 tion, so that the upper face of lip C will be clearly defined. Extending from the upper side of the spherical section is a frusto-conical extension E, the larger diameter being at the upper end. 25

The leading and material features of my design comprise the elements B, C, D, and E, located, as shown, above the shoulder of the body A.

What I claim is—

The design for bottles substantially as 30 shown and described.

In witness whereof I hereunto set my hand in the presence of two witnesses.

SYLVESTER R. CHANDLER.
